UNITED STATES PATENT OFFICE.

ERNEST E. WELLER, OF PROVIDENCE, RHODE ISLAND.

DESIGN FOR A SHOE-STRAP-FASTENER MEMBER.

Application filed July 6, 1928. Serial No. 27,399. Term of patent 3½ years.

To all whom it may concern:

Be it known that I, ERNEST E. WELLER, a citizen of the United States of America, residing at Providence, county of Providence, State of Rhode Island, have invented a new, original, and ornamental Design for a Shoe-Strap-Fastener Member, of which the following is a specification, reference being had to the accompanying drawing, forming a part thereof,

Fig. 1 is a face view and Fig. 2 is an edge view of a shoe strap fastener member, illustrating my new design.

I claim:

The ornamental design for a shoe strap fastener member, substantially as shown.

ERNEST E. WELLER.
